INVENTOR,
Stephen D. Baker,
BY
John L. Townsend,
ATTORNEY

UNITED STATES PATENT OFFICE.

STEPHEN D. BAKER, OF NEW YORK, N. Y.

WALL ELEMENT.

1,255,975.

Specification of Letters Patent. Patented Feb. 12, 1918.

Application filed December 2, 1916. Serial No. 134,628.

To all whom it may concern:

Be it known that I, STEPHEN D. BAKER, a citizen of the United States, residing at New York city, in the county of New York 5 and State of New York, have invented certain new and useful Improvements in Wall Elements, of which the following is a specification.

This invention relates to wall fixtures 10 and particularly to that class of fixtures, especially designed for use in connection with bath tubs or bathing pools, known as "grab rails" or "rising rails", and its object is to provide a fixture or element of 15 this kind which may be set into the wall so as to impart the appearance of sanitary plainness characteristic of the finish of modern bath rooms and in a manner to avoid the use of disclosed securing means and obtain 20 a strong connection with the wall and preserve the latter free from unduly extending projections.

In the accompanying drawing, showing the preferred form of my invention,

25 Figure 1 is a front elevation of the wall-element in position in a wall;

Fig. 2 is a vertical sectional view of what is shown in Fig. 1, on a larger scale;

Fig. 3 is a rear view of the wall-element, 30 showing one form of anchor means; and,

Fig. 4 is a fragmentary view of said wall-element, partly in plan and partly in horizontal section and showing another form of anchor means.

35 In the construction shown, the wall-element is composed of some material of the class used in the ceramic art, so as to conform to wall-tiling; it is cast in one piece.

The two main parts are a cavitary body 40 portion and a rigid bar bridging the cavity of said body portion.

The body portion, in the form shown, includes two parallel counterpart upright side walls *a a* and a wall *b* which joins the walls 45 *a a* and extends from their front edges first backward, then downward and then forward to the front edges of said walls *a a*, in such manner as to leave the upper and lower rear corners *c c* of said walls projecting, producing a cavity *d* that is open 50 at the front. The front or cavity-face of wall *b* is curved and preferably without angles, any horizontal section thereof presenting a straight line from one of the sides 55 or side walls *a* to the other, so that it may

be readily wiped out with a cloth or the like and kept dry and clean.

The hand bar, *e*, is a straight, substantial and preferably cross-sectionally round piece which bridges the cavity, connecting the side 60 walls *a a*; it is arranged horizontally in spaced relation to the upper and lower edges of the wall *b* so as to afford a hand-grip space above and below it. In the form shown the longitudinal axis of the bar is 65 about coincident with the plane of the front edges of the walls *a a*, so that one longitudinal half thereof is within the cavity and the other projects, its outer longitudinal half overlapping the front edges of the walls 70 *a a* so that the bar obtains a strong connection with said walls.

When the wall-element is set in a wall, 75 as *A*, as shown in Figs. 1 and 2, a recess is provided in the wall into which the wall-element will fit fairly snugly. The wall-element is fitted to such recess and by mortar or any other suitable cement secured in place. The walls *a a* afford at their outer 80 faces broad surfaces to which the cementing medium may adhere.

The wall-element may be provided with anchorage means acting, auxiliarily to the cement, to hold it in the wall. Such is indicated at *f* in Fig. 3 as a rod and at *g* 85 in Fig. 4 as a nail or the like, opposed holes *h* in the upper projections *c c* being provided to receive them; the rod and nail are removably arranged in the holes in the present instance.

I do not wish to be limited to the precise construction herein shown and described, what I claim being:

1. A built-in wall element including, with a cavitary body portion formed with planiform sides and with a wall rigidly joining said sides and forming the back and bottom of the cavity, a hand-bar rigidly joining said sides, any horizontal section of said wall presenting at its concave face a straight line from one of said sides to the other and said wall at said face thereof presenting a curve in vertical section rising gradually from the plane of the front face of said body, and the bar leaving a hand-grip space 100 both above and below itself.

2. A built-in wall-element including, with a cavitary body portion formed with planiform sides and with a wall rigidly joining said sides and forming the back and bottom 110

of the cavity, a hand-bar rigidly joining said sides and projecting throughout its length beyond the front of each of said sides, any horizontal section of said wall 5 presenting at its concave face a straight line from one of said sides to the other and said wall at said face thereof presenting a curve in vertical section rising gradually from the plane of the front face of said 10 body and the bar leaving a hand-grip space both above and below itself.

3. A built-in wall-element including, with

a cavitory body portion formed with approximately rectangular planiform upright sides and with a wall rigidly joining said 15 sides and forming the top, bottom and back of the cavity, said sides having rearward corners thereof projecting backwardly beyond said wall, a hand-bar rigidly joining said sides, and anchorage means projecting 20 laterally from the corners of said sides.

In testimony whereof I affix my signature.

STEPHEN D. BAKER.
